UNITED STATES PATENT OFFICE.

LOUIS G. BRINKMAN, OF DAYTON, OHIO.

TOY TELEPHONE.

Application filed October 11, 1924. Serial No. 743,039.

This invention relates to toys and more particularly to toy telephones in simulation of a desk phone. The invention consists especially in features of construction, 5 which enables the toy telephone to be manufactured economically.

Toy telephones of the present general type and of similar appearance are quite commonly manufactured and sold. In common with the typical desk phone such toy embodies a transmitter head and mouth piece, mounted upon the upper end of a post or pedestal supported on a base from which extends a cord connected at its extremity to a receiver supported upon laterally projecting receiver hooks. Such toy telephones are ordinarily provided with a bell, usually of the bicycle type. In many instances, the bell is actuated by the removal of the receiver from the hook and by its replacement. In other instances and as shown in the present drawing, the bell is independently actuated. The particular features of the present invention and mode 20 of assembling can be applied to either form of toy telephone, whether equipped with an automatically actuated bell or an independently operated bell. In the present toy, the post or pedestal is given the appearance of the usual metal standard without, however, necessitating the use of threaded joints, soldering, staking or other such method of attachment for the transmitter head and base, as would be usual 25 in an all metal device. The difficulty of such assembly is obviated, and a simple, convenient and economical method of attachment is afforded by making such supporting post of wood and enclosing it in a 30 thin tubular jacket of metal. This enables the transmitter head to be connected to the upper end of such standard or post by a coupling member stamped from sheet metal and having a projecting tine or finger to be 35 driven into the upper end of the wooden post or standard enclosed in the tubular metallic jacket. Likewise the supporting base is attached to the lower end of such post or standard by a nail, driven into the 40 wooden interior of the post.

To further increase the simulation of the standard phone, the present toy is provided with a glass mouthpiece, which to facilitate its engagement with the stamped metal 45 transmitter head is formed with a rearwardly projecting stud having lateral lugs

which are engageable in a flanged key hole opening in the transmitter head by a partial rotation of the mouth piece after inserting the lugged stud therein. The transmitter head is pivotally connected to the standard or post coupling by means of parallel ears attached to the back of the transmitter head by clenched tines, which ears extend on opposite sides of the coupling member, to which they are pivoted for oscillatory movement. The receiver cord, which ordinarily extends thru a hole in the base in such toy telephone in the present instance is clamped between the wooden interior of the post or standard and the base, where it is secured by the same nail which holds the base and standard in attachment. The metallic tube is notched to accommodate the cord.

The object of the invention is to simplify the construction and mode of assembly of toy telephones, whereby they will be cheapened in construction, capable of being easily and quickly assembled, strong, durable and unlikely to become broken or unjointed.

A further object of the invention is to provide a toy telephone with a simulation of the conventional nickel plated metallic post or standard and glass mouth-piece, while obviating the usual difficult and expensive method of attachment of such parts.

With the above primary and other incidental objects in view as will more fully appear in the specification, the invention 90 consists of the features of construction, the parts and combinations thereof, and the mode of assembly, or their equivalents as hereinafter described and set forth in the claims.

In the accompanying drawings, wherein is shown the preferred, but obviously not necessarily the only form of embodiment of the invention, Fig. 1 is a perspective view of the assembled telephone forming the subject matter hereof. Fig. 2 is a vertical sectional view showing the relation of the several parts and mode of assembly. Fig. 3 is a rear perspective view of the glass mouthpiece. Fig. 4 is an interior view of a portion of the transmitter head showing the flanged key hole slot in which the glass mouth-piece is to be engaged. Fig. 5 is a sectional plan view and Fig. 6 is an interior view of the opposite sides of the transmitter head, illustrating the mode of attaching the transmitter head to the

jointed coupling member. Fig. 7 is a transverse sectional view showing the wooden post or standard enclosed in a tubular metallic jacket in simulation of the conventional nickle plated desk phone standard.

Like parts are indicated by similar characters of reference thruout the several views.

In constructing the present toy telephone there is employed a base 1, stamped from sheet metal of concavo-convex form, to the top of which the post or standard 2 is secured. This post or standard 2 comprises an interior wooden core 3 of cylindrical form, which is enclosed in a surrounding tubular jacket 4. Inasmuch as the jacket 4 sustains no weight and is not subjected to strain, but is merely a mask for the wooden interior core 3, such jacket may consist of very thin tubing, preferably of brass, but which may be of other material or treated to enable it to be nickel plated, or given an otherwise bright finish. The tubular jacket 4 at its base end is provided with a notch 5, thru which extends the extremity 25 of the receiver cord 6. This cord is clamped between the base 1 and the lower end of the wooden post or standard 3. In addition to being clamped, the cord 6 is transfixied by a nail 7, driven thru the base 1 and into the wooden post 3, which secures the base and post or standard in assembled relation. Enclosing the upper end of the jacketed standard or post is a cap piece 8, having therein a slot thru which the transmitter head coupling is driven in the post 3. This coupling member comprises an upstanding plate-like member 9, having projecting from the lower end thereof a tine or finger 10, which is driven thru the slot in the cap piece 35 8, into the upper end of the post 3. Pivottally connected to the upstanding plate-like member 9 are two parallel ears or angle plates 11. These ears or angle plates 11 extend on opposite sides of the upstanding coupling plate 9, to which they are pivotally secured by an eyelet 12. The transmitter head 13 is of circular box-like form, stamped from pieces of sheet metal. The member 14 is formed with a marginal flange, which encloses and fits over the marginal walls of the member 15, in the manner of a box lid. Struck up from the ears or angle plates 11 are tongues or tines 16, which are insertable thru corresponding openings in the rear wall of the member 15, within which with such tongues or tines are clenched in opposite directions to secure the transmitter head members in place. The front piece 14 of the transmitter head is formed with an irregular opening somewhat resembling a key-hole slot. To strengthen and stiffen the transmitter member the margins of this key-hole opening are inturned or flanged as at 17, in Fig. 4. The mouth-piece 18 which is preferably, tho not necessarily of glass is formed

with a rearwardly projecting stud or boss 19, having laterally disposed lugs 20. This boss or stud 19 is insertable thru the key hole slot or opening in the transmitter head piece and thereafter by a partial rotation 70 the lugs 20 are turned transversely of such slot into overhanging relation with the side flanges 21 of such opening, which lateral flanges are of less height thereby accomodating the lugs 20. The inturned flanges 75 21 are proportioned to fit tightly beneath the lugs 20 of the mouth-piece stud, thereby insuring tight locking engagement upon such rotation of the glass mouth-piece. An alarm bell of the bicycle type is shown at 80 22, clamped upon the standard or post. In this instance the bell is actuated independently of the receiver by means of the thumb lever 23. Obviously, other methods of operating the bell may be employed, while utilizing structural features and assembly methods heretofore described. While the receiver hook or arm might be formed integral with the cap piece 8, in the present instance the receiver hook 24 has been shown 90 supported upon the post or standard 2 by means of an integral clamp collar 25. The clamp collar 25 and receiver hook are formed in integral halves connected by clamp bolts 26. From one end of each half 95 the clamp collar 25, there projects one arm of the receiver hook, which is integral with and forms a continuation of the clamp collar section. This construction materially simplifies the construction as well as the assembly. It further enables the receiver hook arms to be disposed edgewise to the direction of strain, making the device stronger and less likely to be bent out of shape. The same clamp collar 25 forms 105 the mounting for the bell 22 which is riveted to one of the collar sections.

To afford a strong and ample support, the margins of the base 1 are inturned or clenched over a disc 27, which may be metal 110 or card board. The bottom is finished by gluing a disc 28 of felt thereto.

The features of construction heretofore described facilitates the manufacture of the present toy economically with unskilled labor. The toy is pleasing in appearance, closely simulating the conventional desk telephone.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language 130

more or less specific as to structural features, it is to be understood that the invention is not limited to the specific details shown, but that the means and construction herein disclosed comprises the preferred form of several modes of putting the invention into effect and the invention is, therefore, claimed in any of its forms or modifications within the legitimate and valid scope of the appended claims.

Having thus described my invention, I claim:

1. A toy telephone including a base supporting a post, which in turn carries a transmitter head and mouth piece, characterized by a wooden post enclosed in a tubular metallic jacket in simulation of the conventional metal standard and members driven into the opposite ends of the enclosed wooden post, to secure the base and transmitter head thereto.

2. In a toy telephone, the combination with a transmitter head and a base of a post or standard comprising a wooden core and a tubular metallic jacket enclosing the core, the transmitter head and base being attached to the wooden core at opposite ends of the post.

3. In a toy telephone, the combination with a base and a transmitter head of an intermediate standard comprising a wooden post and a tubular metallic jacket, enclosing the wooden post and means for attaching the base and transmitter head to the opposite ends thereof.

4. In a toy telephone, the combination with a base and transmitter head, of an intermediate connecting standard comprising a metallic tubular member, and a non-metallic reinforcement member enclosed therein.

5. In a toy telephone, the combination with a base and transmitter head, of an intermediate connecting standard comprising a metallic tubular member having in its lower end a notch, a wooden core enclosed within the metallic tubular member, and a receiver cord extending thru said notch and clamped between the wooden core and the base.

6. A toy telephone including a base supporting a standard, which in turn carries a transmitter head, characterized by a glass mouth piece, an integral stud formed upon the mouth piece and laterally disposed lugs upon the integral stud, said transmitter head

having therein a key hole slot in which the lugged stud is introduced and engaged by a partial rotation.

7. A toy telephone including a base supporting a standard, which in turn carries a transmitter head, characterized by a mouth piece having an integral stud provided with integral lateral projections, said transmitter head having therein a key hole slot in which the stud is insertable and within which it is secured by a partial rotation by which the lateral projections are turned transversely in relation with the slot.

8. A toy telephone including a base supporting a standard which in turn carries a transmitter head, characterized by a mouth piece having a stud provided with lateral projections, said transmitter head having therein a key hole opening to receive the stud and lateral projections carried thereby and a marginal reinforcing flange surrounding the key hole opening over which the lateral projections of the mouth piece stud engage upon partial rotation thereof while within the opening.

9. A toy telephone wherein a base supports a standard which in turn carries a transmitter head, characterized by a single coupling plate projecting from the top of the standard, a pair of parallel spaced angle ears carried by the transmitter head with their base portions oppositely disposed and secured to the transmitter head and their upstanding parallel portion extending on opposite sides of the coupling plate and a pivotal connection between the spaced parallel ears and the plate.

10. A toy telephone wherein a base supports a standard which in turn carries a transmitter head, characterized by a coupling plate projecting from the top of the standard, a pair of spaced angle plates, lines upon said angle plates clenched upon the transmitter head to secure the angle plates thereto in parallel spaced relation, and a coupling plate carried by the standard and projecting intermediate the spaced angle plates, said coupling plate and angle plates being interpivoted for relative oscillatory movement.

In testimony whereof, I have hereunto set my hand this 25th day of September A. D. 1924.

LOUIS G. BRINKMAN.
